CARRYING BAG

Howard L. Israel, New York, N.Y., assignor to Bonne
Age, Inc., New York, N.Y., a corporation of New York

Application June 2, 1959, Serial No. 56,189

Term of patent 14 years

(Cl. D87—3)

Fig. 1 is a side elevational view of a carrying bag embodying my new design;

Fig. 2 is an end elevational view taken from the right hand end of Fig. 1; and

Fig. 3 is an end elevational view taken from the left hand end of Fig. 1.

The appearance of the side of the bag opposite from that visible in Fig. 1 is a substantial mirror image of the appearance of the side visible in Fig. 1 except that the ornamentation on the lower portion is the same as in Fig. 1.

I claim:

The design for a carrying bag, as shown and described.
